(57) **CLAIM**

The ornamental design for a mobile phone as shown and described.

DESCRIPTION

FIG. 1 is a front view of an embodiment of a mobile phone; FIG. 2 is a back view of the mobile phone shown in FIG. 1; FIG. 3 is a left side view of the mobile phone shown in FIG. 1;

FIG. 4 is a right side view of the mobile phone shown in FIG. 1;

FIG. 5 is a top view of the mobile phone shown in FIG. 1; FIG. 6 is a bottom view of the mobile phone shown in FIG. 1;

FIG. 7 is a front right perspective view of the mobile phone shown in FIG. 1;

FIG. 8 is a back right perspective view of the mobile phone shown in FIG. 1;

FIG. 9 is an enlarged view of detail "9" identified in FIG. 1; and,

FIG. 10 is an enlarged view of detail "10" identified in FIG. 5.

The evenly spaced broken lines depict parts of the mobile phone that form no part of the claimed design.

The dot-dash lines are boundary lines, which define the bounds of the claimed design. These boundaries do not exist in reality in the article embodying the design. It is understood that the claimed design extends to these boundaries but does not include the boundaries.

The broken lines comprised of alternating long and short dashes are for the purpose of designating the enlarged portions of the drawings, and form no part of the claimed design.
